UNITED STATES PATENT OFFICE.

ALBERT F. PARKS, OF CHELTENHAM, PENNSYLVANIA.

GAS-ENGINE.

1,070,521.

Specification of Letters Patent. Patented Aug. 19, 1913.

Application filed May 24, 1911. Serial No. 629,127.

To all whom it may concern:

Be it known that J. ALBERT F. PARKS, a citizen of the United States, residing at Cheltenham, county of Montgomery, and State of Pennsylvania, have invented a new and useful Improvement in Gas-Engines, of which the following is a full, clear, and exact description, reference being had to the accompanying drawings, which form a part of this specification.

The object of my invention is to provide a construction more particularly applicable to engines of the two-cycle type, which will overcome certain defects and limitations characterizing the ordinary engines of this type; chief among which may be mentioned the necessity for a closed and absolutely tight crank-case, the insufficient charge exchange from pump to working cylinder, and the very considerable leakage of mixture between the inlet and exhaust ports under partial load conditions.

Figure 1 is a longitudinal sectional view of a gas-engine embodying my invention; Fig. 2 is a longitudinal section on the line 2—2 of Fig. 1; Fig. 3 is a cross-section on line 3—3 of Fig. 1; Fig. 4 is a longitudinal section through the pump cylinder, showing a modification.

a is the crank shaft; b the crank case; c, d, the engine cylinders; e, f, the pistons working therein; and g, h, connecting rods between the crank shaft and the pistons. On one of the pistons (say the piston f) is a laterally projecting lug j, to which is secured the piston rod of a piston i working in the pump-cylinder k. This piston rod is arranged parallel with the axes of the working cylinders and is guided outside the cylinder-walls and preferably inside the limits of the water-jacket space l. In the upper part of the pump-cylinder k is a port q communicating with the chamber m. In the lower part of the pump-cylinder k is a port p communicating with the chamber n. Between chamber m and working cylinder c is an automatic valve r, which to close moves upward against its seat. Between chamber n and working cylinder d is a similar automatic valve s.

t, t, etc., are exhaust ports in the working cylinders, which ports are uncovered in the extreme outward position of the pistons e and f, as in usual two-cycle practice.

u and v are inlet ports to the chambers m and n respectively, through which explosive

mixture from a usual type of carburetor is introduced through check-valves w, one of which is shown in Fig. 1.

The operation of the foregoing construction will be readily understood by one skilled in the art. An expanding charge in the working cylinder d forces down the piston f, which carries with it the piston i in pump-cylinder k, thus compressing the charge in chamber n. The valve s is held closed by the preponderance of pressure in cylinder d up to the moment when the exhaust ports in this cylinder are uncovered in the outward movement of the piston. In the meantime, the descending piston i in pump-cylinder k has created a partial vacuum in chamber m, into which explosive mixture rushes from the carburetor through the check-valve w and port u. At the moment the exhaust ports in cylinder d are uncovered, the remaining pressure in this cylinder immediately drops to that of the atmosphere, valve s opens, and the compressed charge in chamber n flows into cylinder d, completely filling this cylinder and displacing all products of combustion therein remaining; it being understood that cylinders d and k are properly proportioned with respect to areas. Upon the next upward stroke of piston f the charge in cylinder d is compressed, and ignited at the proper instant in the usual manner. During the upward movement of piston f, the piston i compresses the charge in chamber m. When the exhaust ports in cylinder c are uncovered, valve s opens, and this charge flows into cylinder c and is compressed and ignited at 180° from that in the cylinder d.

The construction described is a well balanced form of construction and effects equally spaced power impulses. It permits of a simple form of crank-shaft, an open crank-case if desired, and the use of ball- or roller-bearings practically impossible in the usual form of two-cycle engine construction. The volumetric efficiency of the working-cylinder is increased over the usual type of engine due to the fact that a cylinder full of pure explosive mixture uncontaminated with previous products of combustion is available.

The foregoing description will be recognized as covering what is usually known as a two-port type of engine with automatic inlet valve. If the cylinder k be slightly increased in length, as shown at k', Fig. 4,

and a piston z , of such a length as to uncover the port y at the extremes of its travel be provided, and the carbureter connected at z , omitting a check-valve, the three-port type 5 of engine results.

While my invention is described and illustrated as applied to a two-cylinder type of engine, it is obvious that it is capable of embodiment of a single-cylinder engine, which, 10 indeed, would result if the cylinder c , its piston e , and chamber m were removed.

Having now fully described my invention, what I claim and desire to protect by Letters Patent is:—

15 1. In a gas engine, the combination with a crank shaft, a pair of power cylinders, pistons therein and connecting rods between the power pistons and the crank shaft, of a double acting pump actuated by one of said 20 power pistons, and a compression chamber interposed between said pump and each power cylinder, said compression chambers connecting with opposite ends of said pump, a passage connecting each compression 25 chamber with the corresponding power cylinder and automatic valves in said passages.

2. In a gas engine, the combination with a crank shaft, a pair of power cylinders, pistons therein, connecting rods between the 30 power pistons and crank shaft, and exhaust ports to the atmosphere in each power cylinder, of a double acting pump cylinder, a piston therein, means connecting the pump piston with one of the power pistons where- 35 by they reciprocate in unison, a compres-

sion chamber connected with each end of the pump cylinder, inlet ports to the compression chamber and automatic valves connecting each compression chamber with one of the power cylinders, whereby, at each 40 stroke, the requisite charge is drawn into one of the compression chambers and compressed sufficiently to discharge itself through the automatic valve into the respective power cylinder at the time the exhaust port in the latter is open.

3. In a gas-engine, the combination with a crank shaft, of a pair of working cylinders and power pistons therein, connecting rods between the crank-shaft and pistons, 50 a pump-cylinder and a piston therein, exhaust ports in the working cylinders, a pair of compression chambers, an automatic valve between each compression chamber and the corresponding working cylinder, 55 ports in the pump cylinder arranged respectively above and below the pump piston and communicating with the respective compression chambers, means connecting the pump piston and one of the power pistons, 60 and means permitting ingress of fresh charges of motive fluid alternately to the two compression chambers.

In testimony of which invention, I have hereunto set my hand, at Philadelphia, on 65 this 23rd day of May, 1911.

ALBERT F. PARKS.
